US0D1004290S

(12) **United States Design Patent** (10) **Patent No.:** **US D1,004,290 S**
(45) **Date of Patent:** **** Nov. 14, 2023**

(54) **SHEET WITH SLITS**

(71) Applicant: **3M INNOVATIVE PROPERTIES COMPANY**, St. Paul, MN (US)

(72) Inventor: **Thomas R. Corrigan**, St. Paul, MN (US)

(73) Assignee: **3M INNOVATIVE PROPERTIES COMPANY**, St. Paul, MN (US)

(**) Term: **15 Years**

(21) Appl. No.: **29/744,493**

(22) Filed: **Jul. 29, 2020**

(51) LOC (14) Cl. **05-06**

(52) U.S. Cl.

USPC **D5/60**; D5/99

(58) **Field of Classification Search**

(57) **CLAIM**

The ornamental design for a sheet with slits, as shown and described.

DESCRIPTION

FIG. 1 is a perspective view of a sheet with slits according to the new design;

FIG. 2 is a top view thereof;

FIG. 3 is a bottom view thereof;

FIG. 4 is left side view thereof;

FIG. 5 is a right side view thereof;

FIG. 6 is front view thereof; and,

FIG. 7 is a back view thereof.

The broken lines surrounding the sheet with slits depicts environmental subject matter that forms no part of the claimed design.

1 Claim, 4 Drawing Sheets
